DESIGN FOR A CONTROL CLOCK

Burton E. Shaw, Adel, Iowa, assignor to Penn Electric Switch Co., Des Moines, Iowa, a corporation of Iowa

Application November 10, 1936, Serial No. 65,831

Term of patent 3½ years

To all whom it may concern:

Be it known that I, Burton E. Shaw, a citizen of the United States and a resident of Adel, in the county of Dallas and State of Iowa, have invented a new, original, and ornamental Design for a Control Clock, of which the following is a specification, reference being had to the accompanying drawing, forming part thereof.

Figure 1 is a perspective view of a control clock embodying my invention; and

Figure 2 is a front elevation on a slightly enlarged scale.

I claim:

The ornamental design for a control clock as shown.

BURTON E. SHAW.
